UNITED STATES PATENT OFFICE

KYLE E. STANT, OF CONNERSVILLE, INDIANA

DESIGN FOR A RADIATOR CAP

Application filed June 12, 1931. Serial No. 40,170. Term of patent 7 years.

To all whom it may concern:

Be it known that I, KYLE E. STANT, a citizen of the United States, residing at Connerville, in the county of Fayette and State of Indiana, have invented a new, original, and ornamental Design for a Radiator Cap, of which the following is a specification, reference being had to the accompanying drawings, forming part thereof, in which—

Figure 1 is a side view of a radiator cap showing my new design.

Figure 2 is a front view of the same.

I claim:

The ornamental design for a radiator cap as shown.

In testimony whereof, I affix my signature.

KYLE E. STANT.
